ADELPHIA, PENNSYLVANIA, A CORPORATION OF PENNSYLVANIA.

MACHINE FOR MAKING TESSELLATED LINOLEUM.

1,098,684.

Specification of Letters Patent.

Patented June 2, 1914.

Application filed June 2, 1913. Serial No. 771,162.

To all whom it may concern:

Be it known that we, HENRY A. POTTER, Jr., PETER STOVER, Jr., and WILLIAM MUNZ, citizens of the United States, and residents 5 of the city of Philadelphia, county of Philadelphia, and State of Pennsylvania, have invented a Machine for Making Tessellated Linoleum, of which the following is a specification.

10 Our invention relates to the manufacture of tessellated linoleum from granulated composition and its leading object is to produce fabrics embodying the complete design by a comparatively simple machine having the 15 parts for performing the several functions connected so as to act in synchronous relation.

In the accompanying drawings, Figure 1 20 is a part sectional plan view of a machine embodying our improvements; Fig. 2 is a side elevation of the same; Fig. 3 is a side elevation of a section of the machine showing details of the construction for reciprocating the trays; Fig. 4 is a sectional view 25 taken on the line 4—4 of Figs. 2 and 3; Fig. 5 is a side elevation of mechanism for effecting the desired movement of the fabric; Fig. 6 is a sectional view taken on the line 30 6—6 of Fig. 1; and Fig. 7 is a sectional view taken on the line 7—7 of Fig. 1.

The machine, as illustrated in the drawings, has a frame comprising the longitudinal lower beams 1 supported upon the bearings 2, the longitudinal top beams 3, the end struts 4 through which the beams 1 support the ends of the beams 3 and the bed 5, and the intermediate struts or bearings 6' which are supported by the beams 1 and support the parts 3 and 5.

40 Bearings 6 are anchored at the forward end of the machine and a shaft 7 is journaled therein, the shaft having fixed thereon the belt wheels 8 (containing the peripheral recesses 9) and the register wheels 10 containing the notches 11.

A press at the rear of the machine comprises the head 12 fixed by the bolts 13, and the platen 14 movable vertically beneath the head by the pistons 15 acting in the cylinders 16. Links 17, pivotally connected to 50 the table 5 and platen 14, serve to support a movable continuation of the table to the platen.

Bearings 18, fixed to the platen 14, carry

journal blocks 19 adjustable longitudinally by the screws 20 and a shaft 21 journaled in these blocks, the shaft having fixed thereon the belt wheels 22 (containing the peripheral recesses 23) and the sprocket wheel 24.

Steel belts 25, provided with the cleats 26 for engaging the recesses 9 and 23 and the pins 27 for engaging a backing fabric 28, are carried by the wheels 8 and 22 over the table 5 and platen 14, the fabric being drawn 65 from a roller 29, journaled in the bearings 30, under the rollers 31.

A vertically movable frame is formed by the longitudinal side bars 32 and the transverse end bars 33, this frame carrying trays 70 34 adapted for holding the variously colored granulated composition from which the various tesserae of the design are to be formed and having in the respective bottoms thereof apertures 35 and 36 corresponding 75 to the several figures of the design.

Slides 37 are fixed to the side bars 32 and are movable vertically in the ways formed by the bearings 6' and the guides 38 fixed thereon, the slides carrying the bearings 39 80 of the wheels 40 which are adjustable in elevation by screws 41 journaled in lugs 42 on the body of the slides and threaded in lugs 43 on the bearings.

A bar 44, provided with cams 45 for engaging the rollers 40 to effect the elevation of the trays 34, is movable longitudinally on the wheels 46 which are journaled in the yokes 47, the latter being fulcrumed at one end on the bearings 48 and adjustable at the 90 other end by the screws 49 passing therethrough into engagement with the bearings 50, whereby the rollers are vertically adjustable to regulate the elevation of the bars 44.

Cams 51 at the forward ends of the bars 44 are adapted for engaging the rollers 52 of angle levers 53 which are respectively fulcrumed on bearings 54 and provided with dogs 55 adapted for entering the notches 11 100 of the wheels 10, fixing the shaft 7 and the wheels 8 in the desired position, and, through the belts 25, positioning the backing fabric 28 on the table 5.

A cam 57 on one of the bars 44 is adapted 105 for rocking an arm 58 fixed on a journaled shaft 59 which is provided with the lugs 60 for elevating alternately the valve rods 61

of a hydraulic valve 62, the latter connecting pipes 63, communicating with the cylinders 16, alternately with the feed pipe 64 and the exhaust pipe 65.

5 A motor 66 drives a belt 67 which passes over a pulley 68 revoluble on a shaft 69 which is journaled in bearings 70, the pulley being fixed to the shaft by a clutching mechanism 71, operated by a yoke 72 which 10 is operated by a rod 73 movable longitudinally on the bearings 74 by any one of the several handles 75. A worm 76 on the shaft 69 engages a worm wheel 77 fixed on a shaft 78 which is journaled in the bearings 79, the 15 latter shaft having pinions 80 fixed thereon. A crank shaft 81, journaled in the bearings 82, has fixed thereon the spur wheels 83 which engage the pinions 80 and the sprocket wheel 84 which carries the 20 chain 85 provided with the cam 86. A pitman 87 is operated by the crank shaft 81 and operates the arms 88 pivotally connected thereto by the pin 89 and journaled on a shaft 90 revoluble in the bearings 91, the 25 pin having a weighted pawl 92 fixed thereon. A ratchet wheel 93 is fixed on the shaft 90 and is adapted to be engaged on the forward movement of the pawl 92 when oscillated with the arms 88 by the pitman 87. A 30 lever 94 is adapted to be oscillated on the shaft 90 by a rod 95 which connects it to an arm 96 fulcrumed on the bearing 97, the arm having a roller 98 which is engaged by the cam 86 to move the cam end 99 of the 35 lever 94 against the finger 100 fixed to the pin 89 to disengage the pawl 92 from the wheel 93. As the cam 86 leaves the roller 98, following the disengagement of the pawl 92, it engages a roller 101 on a lever 102 40 which is fulcrumed on a bearing 103, the lever carrying a brake band 104 which engages a brake pulley 105 fixed on the shaft 90. The shaft 90, thus turned in a step by step movement, has a spur wheel 106 there- 45 on which engages a pinion 107 fixed on the shaft 7, the latter being turned intermittently and moving the belts 25 intermittently over the table 5 and platen 14.

50 A pinion 108, fixed on the shaft 69, engages a pinion 109 fixed on the worm shaft 110 which is journaled in the bearings 111. A shaft 112, journaled in bearings 113, has fixed thereon a worm wheel 114, which engages the worm of the shaft 110, and pinions 115 which engage the spur wheels 116 journaled in the bearings 117. An eccentric or crank pin 118 is revolved by the wheels 116 and operates the pitman 119 connecting it with the bearing 120 on the cross bar 121 connecting the cam bars 44.

55 The mechanisms connecting the shaft 69 with the wheels 8 and with the bars 44 are timed in their operations so that these wheels act to advance the belts 25 with the 60 cloth thereon following the action of the 65

bars which causes the cams 45 to elevate the slides 37 and the frame 32 with the trays 34 thereon so that the latter shall clear the tesserae placed on the backing fabric, and as the bars 44 withdraw the cams 45 from the 70 rollers 40 so that the trays move downwardly to engage the backing fabric, the cams 51 engage the rollers 52, rock the angle levers 53 and throw the dogs 55 into corresponding notches 11 to fix the fabric in the 75 desired relation to the trays, through the apertures in which the composition is pressed upon the backing fabric. Simultaneously with the movement of the cams 45 under the rollers 40, the cam 57 elevates the arm 58 80 and rocks the shaft 59, causing a lug 60 thereon to elevate a rod 61 by which the valve 62 is operated to open communication between the pipes 63 and 65, permitting the cylinders 16 to exhaust and the platen 14 to 85 fall.

The sprocket wheel 24 is connected by a chain 122 with a sprocket wheel 123 which is fixed to a spur wheel 124, the wheels 123 and 124 being journaled on a shaft 125 fixed to 90 the head 12. Arms 126, adapted to rock on the shaft 125, carry a roller 127 to which is fixed a spur wheel 128 connected with the spur wheel 124 by an idler 129 journaled on one of the arms. The roller 128 frictionally engages a fabric 130 on a roller 131 95 journaled in the bearings 132, the fabric being drawn under the press head 12 from the roller 133 journaled in the bearings 134, in a step by step movement corresponding to that of the fabric carried by the belts 25, and preventing the tesserae from sticking 100 to the press head.

Having described our invention, we claim:

1. In a machine for making tessellated linoleum, the combination of a bed, belts adapted for carrying a backing fabric over said bed, mechanism for moving said belts intermittently, a plurality of trays adapted for holding composition, said trays having bottom apertures corresponding with the design of the tesserae to be formed, slides for reciprocating said trays, guides for controlling the movements of said slides, a press having a movable platen, mechanism for operating said platen, cam bars for elevating said slides and operating said last named mechanism synchronously, and means for reciprocating said cam bars in synchronous relation to the operation of said first named mechanism. 110

2. In a machine for making tessellated linoleum, a frame having vertical guideways, a bed supported by said frame, a movable frame having thereon trays and slides, 115 said slides being movable in said ways, a longitudinally movable cam bar for elevating said slides, means comprising carrier belts for moving a fabric over said base beneath said trays, and mechanism for inter- 120

mittently operating said means and cam bars in synchronous relation.

3. In a machine for making tessellated linoleum, a stationary frame having guide-ways thereon, a bed carried by said frame, a movable frame having trays thereon, struts movable in said ways for reciprocating said movable frame, journaled belt wheels and belts carried by said wheels for carrying a fabric over said bed beneath said movable frame, a notched wheel fixed in relation to said belt wheels, a fulcrumed lever having a dog adapted for positively engaging said notched wheel, a cam bar adapted for elevating said struts and rocking said lever, and means for intermittently moving said bar and wheels in synchronous relation.

4. In a machine for making tessellated linoleum, a stationary frame having vertical 20 guide-ways, a bed carried by said frame, a movable frame having trays thereon, struts movable in said ways to elevate said movable frame, a reciprocating cam bar for elevating said struts, a journaled shaft having 25 belt wheels thereon, belts carried by said wheels over said bed, a motor, and mechanism operated by said motor whereby said shaft and bar are intermittently operated in synchronous relation.

5. In a machine for making tessellated linoleum, a stationary frame having guide-ways thereon, a bed carried by said frame, a press having a reciprocating platen provided with bearings at one end of said 30 frame, fluid pressure mechanism for reciprocating said platen, a movable frame having slides movable in said ways, trays movable by said frame last named to and from said bed, a shaft journaled in said bearings, belt 35 wheels fixed on said shaft, bearings at the other end of said frame, a shaft journaled in said bearings last named, belt wheels fixed on said shaft last named, belts carried by said wheels over said bed and platen, mov- 40 able bars having cams for operating said fluid pressure mechanism and slides in synchronous relation, and means for intermit- 45

tently moving said belts and bars in synchronous relation.

6. In a machine for making tessellated linoleum, a stationary frame, a bed carried by said frame, a movable frame having trays thereon disposed above said bed, means comprising reciprocating bars for moving said frame last named, a press having a reciprocating platen, fluid pressure mechanism operated under control of one of said bars, carrier mechanism comprising belt wheels and belts for moving a fabric over said bed and platen, and means whereby said bars and carrier mechanism are operated in synchronous relation.

7. In a machine for making tessellated linoleum, a bed, a tray movable over said bed, a press having a head and a platen 65 adapted to reciprocate beneath said head, means for moving a fabric intermittently over said bed and platen, means for moving a fabric between said head and fabric first named in synchronous relation to the movement of said means first named, and means for moving said platen and tray in synchronous relation with the movement of said means first named.

8. In a machine for making tessellated linoleum, the combination of a bed, a tray adapted to reciprocate above said bed, a press having a platen at the end of said bed, means comprising a cam bar for reciprocating said tray and platen in synchronous relation, mechanism for moving a fabric over said bed and platen and reciprocating said bar in synchronous relation, and means operated by said cam bar for stopping said mechanism.

In testimony whereof we have hereunto set our hands this 28th day of May, 1913, in the presence of the subscribing witnesses.
